IMPLEMENT FOR PERFORATING A CIGARETTE

Orville L. Stamm, Chicago, Ill.

Application August 6, 1954, Serial No. 448,236

2 Claims. (Cl. 131—170)

This invention relates to an improved method and apparatus for enhancing the smoking quality of tobacco products and more particularly to a method and apparatus for the reduction of all sources of irritation to which tobacco smokers are normally subjected.

It is a principal object of this invention to provide an improved method and apparatus for the reduction of all characteristics of tobacco smoke which might cause irritation to the smoker.

It is therefore a further object of this invention to reduce characteristics of tobacco smoke which might either directly cause or aggravate infection or disease.

It is another object of this invention to reduce the temperature of the inhaled gases resulting from tobacco smoking.

It is a further object of this invention to reduce the tars and irritants present in a given quantity of the gases inhaled by a tobacco smoker.

It is another object of this invention to improve the taste quality of tobacco smoke.

It is another object of this invention to provide an implement for treating cigarettes whereby the harshness and irritation sometimes accompanying smoking are greatly reduced.

It is another object of this invention to provide a portable device for accomplishing the reduction of irritants in tobacco smoke and more particularly a device adapted for pocket transportation.

It is a still further object of this invention to provide a method and apparatus by which the tars and irritants present in a given average cigarette smoke inhalation are reduced up to 40% while the temperature of the smoke inhaled by the average smoker is reduced as much as 20° F.

Further and additional objects will become manifest from a consideration of this specification, the accompanying drawings and the appended claims.

In one form of this invention an elongated pocket device is provided having clip means for engagement with the user's pocket when the device is being transported. More particularly the device comprises a base portion having a pair of elongated arcuate side members extending upwardly therefrom to generally define a cylindrical area adapted to receive a cigarette. Extending upwardly from the base into the cylindrical area are a plurality of aligned spikes or points adapted to perforate the paper wrapper on a given cigarette providing spaced holes of predetermined size whereby cooling air is mixed with the smoke normally passing through the cigarette.

For a more complete understanding of this invention reference will now be made to the accompanying drawing wherein:

Fig. 1 is a perspective view of one embodiment of this invention;

Fig. 2 is a front plan view of the embodiment of Fig. 1 showing a cigarette in dotted lines as it would normally

2

appear when being operated upon by a device constructed in accordance with this invention;

Fig. 3 is a side view of the embodiment of Fig. 1;

Fig. 4 is a rear view of the embodiment of Fig. 1;

Fig. 5 is an enlarged sectional side view of the embodiment of Fig. 1 taken on the line 5—5 of Fig. 2; and

Fig. 6 is a top plan view of the embodiment of Fig. 1.

Referring now to the drawings and more particularly to Fig. 1 a device 10 comprising one embodiment of this invention adapted for accomplishing the method taught by this invention is shown. The device comprises an elongate planar base web 12 having a plurality of spikes or points 14 integrally formed therewith and punched outwardly generally transverse thereto. A pocket clip

16 is formed at one end of the base 12 and is appropriately shaped and folded to overlie a portion of the web 12. As shown in Fig. 3, the free end 18 of the pocket clip 16 is formed inwardly to resiliently engage the base 12 to provide means for maintaining the device on a web member such as a pocket or the like. Formed along the two longitudinal edges of the base 12 are two flanges 20 and 22 which partially overlie the base. Along the otherwise free edges of flanges 20 and 22 arcuate or concave web portions 24 and 26 extend outwardly from the base

25 in spaced relationship to define a generally cylindrical area therebetween. The free edges 28 and 30 of the arcuate portions 24 and 26 are flared outwardly somewhat to form a divergent receiving space into which a cigarette may be deposited and forced inwardly into the 30 cylindrical area between the arcuate portions 24 and 26. The overlying flanges 20 and 22 provide limited resiliency whereby the arcuate portions yield sufficiently to permit insertion of a cigarette.

The manner in which a cigarette is placed into the device 10 is illustrated in the front plan view of Fig. 2 wherein a cigarette is indicated by the dotted lines 32 and is shown in place between the arcuate surfaces 24 and 26 of the device 10. The precise manner and degree to which the spikes 14 penetrate the cigarette wrapper and contents is indicated in Figs. 5 and 6. Therein it can be seen that the spikes 14 are forced into the cigarette indicated by the dotted lines 32 to a limited and predetermined extent.

The spikes 14 have tapered shapes so that the degree 45 of insertion into the cigarette is critical, as this determines the size of the holes produced. It is important to the satisfactory method and apparatus taught by this invention that the punctures and apertures formed in the cigarette be of an appropriate and predetermined size.

Generally the apertures will be very small, the dimensions 50 thereof being of the order of 1 square millimeter or less and spaced approximately 1/2" apart in one particular embodiment of the invention. It is found that apertures of this general size and spacing are adequate to introduce the desired amount of fresh clean air into the cigarette to substantially reduce both the temperature of the smoke passing through the cigarette and the percentage by weight of tars and dust in the smoke while maintaining all of the desirable smoking quality.

In one scientifically controlled experiment comparing the temperature of smoke passing through various cigarettes, and the amount of tars and dust present in such smoke, a striking and convincing difference was found between the smoke of a cigarette smoked in its unmodified form and an identical cigarette taken from the same package smoked in its modified form after being operated upon by the apparatus disclosed herein and in accordance with the method described. Utilizing a regular length cigarette of standard manufacture it was determined that 6.13 milligrams of tars and dust are inhaled by a smoker in taking ten average puffs or inhalations there-

on. When the same test is performed upon an identical cigarette modified in accordance with this invention, that is having spaced apertures aligned longitudinally along the length of the cigarette, the weight of tars and dust inhaled by the smoker taking ten average puffs on said cigarette was reduced to 4.07 milligrams or about 66% of the tars and dust present in an unmodified cigarette. Each puff, it was found in tests using human subjects, produced all of the pleasurable sensations whether the cigarette was modified in accordance with this invention or not and, in fact, in most cases human subjects found that smoke inhaled in a cigarette modified in accordance with this invention is more pleasurable because of the reduced temperature, tars, and dust of the inhaled smoke.

The temperature of the inhaled smoke was measured in a series of tests using human subjects and thermocouples contained within the oral area of the subjects. It was found that the temperature of smoke in the subject's mouth increased as the test progressed and the cigarette became shorter. In smoking a regular cigarette in unmodified form, the temperature of the smoke as it entered the smoker's mouth at the beginning of the test was approximately 76° F. and the temperature increased during the test until, at the end of the tenth inhalation, the temperature had increased to 115° F. and the cigarette was reduced to a butt approximately 1/2" long. In a similar test conducted with a cigarette modified in accordance with this invention the temperature of the smoke inhaled after the first inhalation was on the average 73° F. and after 10 puffs the temperature had increased to only 96° F., thus indicating that a substantial reduction in average smoke temperature is accomplished by the teaching of this invention.

While it is true that for a given inhalation on the modified cigarette less tobacco is consumed than in an identical inhalation with a standard unmodified cigarette, this is considered to be a benefit rather than a detriment in that all of the pleasure and satisfaction is still present in a puff on the modified cigarette and, in many cases, an actual improvement and increased pleasure is registered by the user.

One particular device adapted for portable use and pocket wear is shown and described in this specification.

While applicant has found that one particularly satisfactory modified cigarette includes four apertures having an area of approximately 1 square millimeter and being spaced apart in the order of 1/2" and centrally disposed along the length of the cigarette, the precise size and arrangement of apertures may depend upon the taste of the individual smoker, the firmness of the tobacco and various other factors. If a cooler and more dilute smoke is desired by the user a greater number of apertures more closely spaced or the same number of apertures, each aperture having a larger diameter, may be employed. All of these variations, however, are clearly within the scope of this invention.

Without further elaboration, the foregoing will so

fully explain the character of my invention that others may, by applying current knowledge, readily adapt the same for use under varying conditions of service, while retaining certain features which may properly be said to constitute the essential items of novelty involved, which items are intended to be defined and secured to me by the following claims.

I claim:

1. A one piece device for perforating a cigarette to modify the smoking quality thereof, comprising an elongated substantially channel shaped body having a flat base portion and resilient arms extending from opposite edges thereof defining the sides of the channel, said arms having web portions extending from said base and converging toward each other, and terminating in a plane spaced above said base and defining an open zone therebetween, said arms terminating in cylindrically curved gripping portions joined to said web portions in said plane, and having outwardly flared free ends, and defining a continuation of said zone for resiliently releasably receiving and gripping a cigarette spaced above said base in a position tangent to said plane, a plurality of aligned spikes spaced longitudinally on said base and extending upwardly from said base and having tapered points extending into said zone above said plane a distance less than the distance between said plane and said base, whereby a standard cigarette gripped in said zone will be perforated by said points at spaced intervals along the line of tangency of said cigarette and said plane to a depth substantially less than the radius of the cigarette.

2. A device as set forth in claim 1 and including a resilient pocket clip comprising a resilient tab extending from one end of said base and overlying and urged toward said base exteriorly of the channel shaped body.
